ATTORNEY

UNITED STATES PATENT OFFICE.

JAMES O. LEWIS, OF TULSA, OKLAHOMA.

APPARATUS FOR EXTINGUISHING FIRES IN FLOW LINES.

Application filed December 31, 1926. Serial No. 158,279.

My invention relates to apparatus for arresting explosions in flow lines and more particularly to apparatus of this character for use in connection with lines through which air under pressure is supplied to oil sands for supplementing natural rock pressure to increase the flow of oil to producing wells.

In supplying artificial pressure medium for this purpose it is customary to connect one of the wells in a group with an air compressor, whereby air is forced into the connected well and from it through the sands to the producing well, the air acting as a mechanical propeller on the liquid petroleum and itself becoming saturated with hydrocarbon components of the petroleum during its flow.

The liquid petroleum is pumped or otherwise withdrawn from the producing well and the saturated air treated to recover its hydrocarbon content and then reused by being conducted back together with sufficient atmospheric air to make up the losses to the compressor and thence again through the line to the air well.

It is impossible to recover all of the hydrocarbon content from the air, sufficient of such content remaining in the air after the recovery treatment to constitute the air an explosive mixture, which, if ignited from lightning or other causes, will burn in the line and induce explosions which are destructive to the line and other equipment.

The present invention is directed to improved means for extinguishing flame in the line and the object of the present invention is to supply and control the supply of fire extinguishing material to the line when the same may be required.

In accomplishing this object I have provided improved details of structure, the preferred forms of which are illustrated in the accompanying drawings, wherein:—

Fig. 1 is a perspective view of a flow line equipped with explosion arresters and served with fire extinguishing apparatus in accordance with my invention.

Fig. 2 is an enlarged central longitudinal section of one of the explosion arresters, illustrating the fire extinguishing equipment.

Fig. 3 is a cross section on the line 3—3 of Fig. 2.

Fig. 4 is an enlarged detail perspective view of one of the arrester plug disks.

Fig. 5 is an enlarged detail perspective

view of part of the extinguisher bottle nozzle.

Referring more in detail to the drawings:—

1 designates a flow line which may connect an air well in the field with a compressor (not shown) and interposed in which at spaced intervals are explosion arresting devices indicated generally by the numeral 2.

Each of said explosion arresting devices preferably comprises in detail a housing comprising a pair of facing bells 3 and an intermediate barrel 4, the bells and the barrel having flanges 5 and 6 for clamping the disks 7 forming the end members of the explosion arresting plug, the disks being packed between the bell and barrel flanges by gaskets 8 to seal the structure, and the bells and barrel being securely connected to form a unitary structure by the bolts 9 which extend through apertures in the bell and barrel flanges and through apertures 10 in the plug disks.

The space in the barrel between the disks 7 is filled with granular material, such as sand or gravel, forming a reticular plug 10' of such density as to permit flow of air therethrough but retard flame to prevent ignition of the combustible fluid mixture passing from the chamber in one end of the device to the chamber in the other end thereof.

The disks 7 have apertures 11 of sufficient number and size to permit flow of the fluid from the incoming chamber to the plug and from the plug to the outgoing chamber, the combined flow area of the apertures 11 being at least equal to the cross sectional area of the housing chambers in order to avoid obstruction of the flow.

At the center of each of the disks 7 is an aperture 12 and extending through said apertures and through the granular material located therebetween is a cylinder 13 the ends of which project into the respective housing chambers, the end of the cylinder located within the outgoing chamber being closed, thereby constituting the cylinder a bottle having its mouth opening into the intaking chamber.

Located adjacent to the flow line 1 is a container 14 for a fire extinguishing fluid and extending along the line 1 is a manifold conduit 15, connected with the container by a pipe 16 provided with a control valve 17.

Leading from the manifold conduit 15 are branches 18, each of which extends to and is

preferably threaded into a socket 19 in one of the explosion arresting device housings. Located interiorly of each of said housings is a pipe 20 which extends into the bottle 13 therein and terminates in an open mouth adjacent the closed end of the bottle. Surrounding the pipe 20 adjacent its extreme end and filling the annular space between the branch and the inner wall of the bottle is a ring 21 of fusible material, whereby fire extinguishing fluid passing from the container 14 through the manifold 15, branch 18 and pipe 20 is confined within the base of the bottle and prevented from passing into the housing chamber under normal conditions.

Assuming the flow line to be equipped with the explosion arresting devices and the lines equipped with the fire extinguishing apparatus, the operation is as follows:—

Under normal conditions air-gas mixture forced through the line from the compressor will pass successively through the explosion arresting devices and eventually into the air well, and from thence through the oil sands to increase production from the producing well. Should the artificial pressure medium become ignited in the line, the burning fluid will pass through the line until it enters the intake chamber of one of the explosion arresting devices. Upon encountering the reticular plug in said device the flame will be arrested but may continue to burn within the intake chamber. Unless extinguished this flame will eventually generate sufficient heat to destroy the device and burn back through the plug and ignite the mixture at the opposite side; but with the housing equipped with my improved apparatus when burning fluid has raised the temperature within the housing to a determined degree, the fusible plug in the base of the bottle nozzle will melt, thereby freeing the confined fire extinguishing fluid which is under high pressure so that the latter is delivered from the mouth of the bottle nozzle into the intake chamber of the housing, where it smothers the flame and extinguishes the fire, thereby avoiding destruction of the equipment immediately adjacent the arresting device and preventing repeated explosions further along the line, but limiting the damage to a purely local point.

What I claim and desire to secure by Letters Patent is:—

1. In combination with a flow line, a housing in the line, a flame arresting element in the housing, a bottle having a mouth opening to said housing, a conduit for fire extinguishing fluid projected into said bottle, and a rupturable seal normally obstructing flow through said bottle about the conduit. 55

2. In combination with a flow line, a housing in said line having cross-sectional area greater than that of the line, a reticular plug in said housing, forming end chambers within the housing, a bottle in said plug having its mouth open to the chamber at the intake end of the housing, a conduit extended through the housing into the bottle, and a fusible member sealing the bottle about the conduit to normally obstruct flow of extinguishing fluid from the conduit through the bottle to 70 the housing chamber. 65

3. In combination with a flow line, a plurality of housings interposed at spaced intervals in the line, a flame arresting element in each of the housings, a container for fire extinguishing fluid, a manifold conduit connected with the container, a branch leading from said manifold conduit to each of said housings, and a rupturable sealing element for each of said branches normally obstructing flow from 80 the container to a respective housing. 75

4. In combination with a flow line, a housing in said line including bell members forming end chambers, a reticular plug intermediate the bell members, a bottle member extending through said plug with its closed end located in one of said chambers and its open end in the other chamber, a conduit terminating in the closed end of the bottle, and a fusible member normally sealing the 90 bottle. 85

5. In combination with a flow line, a housing in said line including bell members forming end chambers, a reticular plug intermediate the bell members, a bottle member extending through said plug with its closed end located in one of said chambers and its open end in the other chamber, a conduit extending through the wall of the housing and into the bottle, and a fusible packing in the bottle about the conduit, normally obstructing flow from the conduit to the intake to the housing. 95 100

In testimony whereof I affix my signature.

JAMES O. LEWIS.
